UNITED STATES PATENT OFFICE.

HARRY LANDSLEDEL, OF POPLAR BLUFF, MISSOURI, ASSIGNOR, BY MESNE ASSIGNMENTS, TO THE DALTON ADDING MACHINE COMPANY, OF CINCINNATI, OHIO, A CORPORATION OF OHIO.

ADDING AND RECORDING MACHINE.

1,249,124.

Specification of Letters Patent. Patented Dec. 4, 1917.

Application filed June 11, 1913. Serial No. 778,085.

To all whom it may concern:

Be it known that I, HARRY LANDSLEDEL, a citizen of the United States, residing at the city of Poplar Bluff and State of Missouri, have invented a new and useful Adding and Recording Machine, of which the following is a specification:

This invention relates to adding machines of the type which embody a set of numeral keys equal in number to the number of digits, and by successive operations of which any desired numbers may be set up or introduced into the machine preliminary to adding operations.

15 In the embodiment of my invention which I have illustrated in the accompanying drawings, the adding mechanism is co-operatively related to recording mechanism by operation of which the numbers, set up or introduced into the machine, may be recorded. The adding and recording mechanisms automatically co-operate so that the numbers which are recorded or listed are automatically added. The machine also includes mechanism for co-operating the adding and recording mechanisms in clearing operations.

My invention includes a frame or support containing a series of rows of movable parts, shown in the form of pins in the present instance, in combination with a series of key controlled elements operable to set said part or pins to represent numbers, and including essentially means under the control of a previously set pin in one row for setting a pin of corresponding value in an adjacent row incidentally to said subsequent operation of a numeral key to set another digit in the number. For instance, in the setting of numbers in the machine of my invention, the depression of a numeral first sets a pin in units row of corresponding value to the key so depressed; subsequent depression of the same or another key causes the pin first set to set a pin of corresponding value in tens row, while the key so subsequently depressed sets a pin of corresponding value in units row; subsequent depression of the same or another key causes the pin in tens row to set a pin of corresponding value in hundreds row, and causes the pin which was set in units row to set a pin of corresponding value in tens row, while the depression of the key results in the setting of a pin of

corresponding value in units row. It will be noted that this setting operation is effected independently of any lateral movement of the frame or support containing the pins, and is effected by means under control of each pin for setting a pin of corresponding value in an adjacent row incidentally to the subsequent operation of any of the numeral keys.

After the pins have been set to represent a number as aforesaid the adding mechanism may be operated to add the number represented by said pins, and, when recording mechanism is contained in the machine, the number may also be recorded or listed. Provision is made for automatically releasing the set up pins and restoring them to their idle or initial positions incidentally to operation of the adding or recording mechanism. Repeat mechanism is also provided and is settable at the will of the operator to prevent the set up pins from being returned to their idle or initial positions, and to permit repeated operations of the adding or recording mechanism to add or record the same number more than once without the necessity of successively resetting the number in the machine. After a number has once been added or recorded the value thereof may be increased by operating another numeral key, such, for instance, as the key representing "0", in order to change a value of the previously set number in decimal ratio, as required in multiplication.

In some classes of work demanded of computing machines, and of adding and listing machines, it is necessary simultaneously to add or to add and list two or more columns of numbers or items. My invention also includes mechanism under the control of the operator whereby the single set of ten numeral keys may be caused to set up pins representing two or more items or numbers in separate columns. Necessary correlated mechanism is provided whereby the setting of a number in one column will not affect the pins previously set to represent a number in another column; in other words, provision is made for interrupting the effective operation of the device whereby a set up pin in one row sets a pin of corresponding value in another row incidentally to the subsequent operation of a numeral key, in

order that, after a number has been set up in one column the pins representing said number will not be affected by the setting of pins to represent a number in another column. The repeat mechanism is also capable of use to enable repeated addition or listing of parallel columns of numbers.

In event of error or mistake in operating the numeral keys, and thereby setting up one or more wrong digits, the pins which had been set to represent the digits of the number may be displaced and returned to their idle or initial positions before operating the adding or recording mechanisms. The incorrect number may thereby be canceled or dissipated or erased from the number setting mechanism before entering into the adding mechanism or into the recorded lists of items or numbers. The power required to operate the error correcting mechanism is slight and consists only of sufficient power to set or position "0" pins in the rows corresponding to the pins which had been set by the number keys. The mere act of setting the "0" pins incidentally permits automatic return of digit pins which had been set by the number keys, and without any movement of the pins supporting frame which continues its stationary position.

It will appear from the appended description of the mechanism in detail that the means which operates incidentally to the operation of the numeral keys to set a pin in one row of corresponding value to a pin set in an adjacent row in a preceding operation, is automatic, and is actuated by a suitable motor device and escapement mechanism, so that there is no increase in the manual work as the value of the number increases, but the touch of the keys is constant and uniform throughout.

In the accompanying drawings I have illustrated a preferred embodiment of my invention, and in said drawings

Figure 1 is a perspective view of a complete adding and listing machine in which my invention is embodied.

Fig. 2 is a longitudinal vertical sectional view of the machine, approximately on the line B—B of Fig. 4, illustrating in section the number setting mechanism, and also the adding and printing mechanisms.

Fig. 3 is another longitudinal sectional view, approximately on the line A—A of Fig. 4, illustrating the column space mechanism whereby the number setting mechanism is adjusted for operation in which separate columns of numbers may be set up primarily to adding and recording operations.

Fig. 4 is a partial sectional view, approximately on the line D—D of Fig. 3, and illustrates the arrangement of the number setting mechanism and the coöperating motor and escapement.

Fig. 5 is a sectional view approximately on the line C—C of Fig. 4.

Fig. 6 is a perspective view of a number of the numeral key levers forming a part of the number setting mechanism, and a part 70 of the escapement control mechanism which is controlled by the key levers.

Fig. 7 is a sectional view of the escapement motor device.

Fig. 8 is a sectional view on the line 8—8 75 of Fig. 7.

Fig. 9 is an enlarged plan view of the pin frame and the coöperating mechanism.

Fig. 10 is a perspective view of a "movable basket" controlled by the numeral keys 80 and motor effectively to set the pins in the pin frame to represent selected numbers.

Fig. 11 is a diagrammatic perspective view illustrating the mode of coöperation between the "movable basket" and the pins 85 in the pin frame whereby said pins may be set to represent selected numbers.

Fig. 12 is an enlarged perspective view of the complete pin frame and the "movable basket".

Fig. 13 is a detail view of the devices which are operated incidentally to the operation of the machine to store up power in the motor device, and to render the numeral keys inoperative as an incident to discharge 95 or removal of effective power from the motor device.

Fig. 14 is an enlarged detail view of a part of the mechanism by which numbers are cleared from the pin frame and by 100 which error may be corrected, by setting the "0" pins and permitting simultaneous return of other pins to their idle or initial positions.

Fig. 15 is a detail sectional view of a part 105 of the printing mechanism, illustrating the coöperating devices for separating the printing mechanism into separated units or columns to permit operation of the machine in listing parallel columns of numbers. 110

Fig. 16 illustrates a part of the connections for effecting coöperation between the number setting mechanism and the recording mechanism to permit simultaneous listing of numbers in parallel columns.

Fig. 17 is a perspective view of one form of a device adjustable to separate the printing mechanism into separated units or columns.

Fig. 18 is a perspective view of the complete train of connections whereby the number setting mechanism may be rendered operative as required to permit setting up thereof numbers to be listed in separated parallel columns.

Fig. 19 is an enlarged detail view of the key actuated parts which coöperate with the "movable basket" to set up numbers in the pin frame.

Fig. 20 is a perspective view of the sup- 130

porting frame for a movable carriage in which the levers which are acted upon by the keys may be mounted.

Fig. 21 is a perspective view of the element whose position determines the number of orders in which pins may be set in the pin frame when the "movable basket" operates.

Fig. 22 is a perspective view of the carriage which supports the elements that cooperate with the numeral key levers and the "movable basket" to enable the "movable basket" to set the pins in the pin frame to represent selected numbers.

Figs. 23 and 24 are views of the different forms of the key controlled elements which cooperate the "movable basket" to enable the "movable basket" to set the pins in the pin frame to represent the desired numbers.

Fig. 25 is a perspective view of a part of the type-carrier control mechanism which enables the pins which had been set to represent numbers, to be returned to their idle or initial positions before return of the type-carriers.

Fig. 26 is a detached perspective view of an element included in the repeat mechanism arranged to prevent operation of the clearing mechanism at all times when transferring or carrying is incomplete.

The machine in which I have illustrated my invention includes a set of ten numeral keys 1 attached to the upturned ends of levers 2. The levers 2 converge toward the center of the machine and are provided with arms 3 which extend substantially parallel with the body of the levers, and which have their ends pivotally supported upon a shaft 4. The arms 3 constitute resilient supports for the key levers, so that when undue force is employed by the operator in striking the keys the shock is absorbed in the resilient mounting of the levers and is imparted to or thrown against any of the mechanism to be acted upon by the levers. The key levers are of various lengths, and in the embodiment shown the "0" key lever extends farthest to the rear, the "1" key lever being of the next greatest length, the "2" key lever terminating next, and so on through the entire series of levers, which renders the "9" key lever the shortest one of the series. Each key lever is preferably provided at its rear end with an upturned portion or extension 5. Springs 6 connect the rear portions of the key levers with a lower frame part of the machine and serve to restore the levers to idle position after operation.

At the rear of the machine and to the right of the key levers (as the operator faces the machine) is a carriage support 7, (Figs. 4, 5 and 20), including two parallel rails or track members 8. A carriage 9 which, in the embodiment shown, is in the form of a horizontal plate provided with two downwardly extending ends, has rollers

10 operating within grooves formed in the inner faces of the rails 8. The carriage is movable from one position to another, as hereinafter described in connection with the description of the operation of the machine in listing parallel columns of numbers, and the rails above and below the rollers 10 serve as positive retaining devices to prevent derailment of the carriage. The ends of the carriage support shaft 11 and a rod 12, A series of transverse levers 13, in the present instance equal in number to the number of key levers, are pivoted to the shaft 11 and rest upon the rod 12, each of the levers 13 extending transversely over the upturned end 5 of the corresponding numeral lever. The weight of the levers 13 is sustained by the rod 12, said levers being actuated downwardly upon said rod 12 and adjacent to the ends of the corresponding numeral levers by suitable springs 14 connecting said levers with the carriage in which they are mounted. Each of the levers 13 is provided with a projecting hammer portion 15, the entire series of hammers 15 being side by side in a row in the machine. The levers 13 are of different lengths, each lever being arranged to extend from the shaft 11 to a position immediately above the key terminal 5 with which it is arranged to cooperate. From the foregoing it will be understood that the numeral levers 2 control the levers 13.

A stationary frame 16, (Figs. 2, 4, 9 and 12), is supported above the ends of the numeral levers 2 and above the levers 13, by means of standards 17, which rest upon the base of the machine and constitute rigid supports for the frame. The frame 16 includes a top plate 18 and a bottom plate 19, and a series of parallel guides 20 attached to the upper side of the top plate. The guides 20 form parallel channels corresponding to a number of numerical orders. Adjustable pins 21 are supported by the top and bottom plates of the frame and may be raised into the channels between the guides 20 as a result of the operation of the numeral keys. When so raised said pins represent the numbers to be added or listed. Each pin is encircled by a spring 22 tending to actuate said pin downwardly. Adjacent to each row of pins 21 for each numerical order is a longitudinally movable latch plate 23 having pins 24 extending alongside of the pins 21. The plates 23 are actuated in one direction by springs 25, (Fig. 2). Each pin 21 is formed with a shoulder 26 which, when said pins 21 are raised, engage over the pins 24 and thereby latch the pins 21 in elevated position in which their upper extremities are within the channels between the guides 20.

At this point it appears appropriate to mention that there is one row of pins 21, with which no train of adding or recording mechanism cooperates, so that there is one

additional row of pins 21 in addition to a number of other rows, each of which other rows coöperates with a train of adding or recording mechanism. It is through the co-operation of this additional row with the keys and the levers 13 that the pins in the other rows may be set to represent numbers. The additional row of pins 21 with which no train of adding or recording mechanism coöperates, is indicated at X in Fig. 4.

In the normal or usual position of the carriage 9 the row of hammers 15 are immediately below the lower ends of the additional or extra row of pins, (Fig. 12), so that when any numeral key lever is operated a pin 21 of corresponding digital value will be raised in the extra or additional row of pins as a direct result of and immediately upon the depression of the numeral key. By means of coöperating devices the pin so positioned by the depression of the numeral key sets a pin of corresponding value in the adjacent row of pins with which a train of adding and recording mechanism coöperates, and subsequent operations of any of the numeral keys result in stepping the digits of the number from order to order by setting the necessary pins of corresponding value in the different orders until the entire number has been set up by the pins 21. It will be observed that the means for setting the pins of corresponding value in adjacent rows incidentally to subsequent operations of numeral keys is under control of pins of corresponding value set by a preceding operation of a key previously operated. It will be further observed that the field of pins does not move from order to order, but that the pins themselves control the order to order stepping mechanism, and that the stepping mechanism is automatic in its operation and takes place as an incidental result of the operation of the numeral keys.

Below the pin frame 16 is another frame 45 which includes two side members 27, (Figs. 10, and 12), united by suitable tie-rods 28. The side members 27 have downwardly extending arms, the arms at the rear being pivoted to levers 29 which are supported upon a shaft 30 and the arms at the front being pivoted to levers 31 which are attached to a rock shaft 32. The ends of the levers 29 and 31 are connected by pin-and-slot connection 33, so that the adjacent ends of said levers move vertically in unison to raise and lower the frame 27, whenever the rock shaft 32 is rocked. The frame 27 is raised and lowered as an incident to the operation of each numeral key through connections operated by a motor and escapement device which is under control of the numeral keys, and which I will now describe. A universal bar 34 (Figs. 4 and 6) extends across the upper edges of the numeral key levers 2 and 65 rearwardly from the shaft 4 upon which

said levers are pivoted, and is attached to two arms 35 whose rear ends are attached to a rock shaft 36 which is mounted in suitable supporting brackets attached to the base of the machine. An escapement member 37 is attached to the rock shaft 36, and another escapement member 38 is pivoted upon said rock shaft 36 adjacent to the member 37, and is actuated toward said member 37 by a connecting spring 39, being limited in its movement by a projecting lug 40 on the member 37. An escapement ratchet wheel 41 is embraced between the escapement members 37 and 38. The wheel 41 is rigid upon a hub or bushing 42 mounted upon a shaft 43. The said escapement ratchet 41 is also in rigid connection with a motor-spring drum or casing 44. A motor-spring 45 is inclosed within the drum or casing 44 and has one end attached to said drum or casing and the opposite end attached to a sleeve 46 which is mounted on the shaft 43 (Fig. 7). Assuming that power is stored in the spring 45 it is clear that, when a numeral key is operated the escapement ratchet 41 will escape between the escapement members 37-38, being actuated by the power in the spring 45. A cam disk 47 is attached upon the hub or bushing 42 and is, therefore, rotated in unison with the escapement ratchet 41. The cam disk 47 is formed with a number of cam projections upon its periphery, there being one of said cam projections for each tooth or step-space through which the escapement pinion or ratchet 41 moves when operated as aforesaid. The cam disk 47 operates upon a small roller 48 which is supported upon a stud or pin on the front end of a lever 49 attached to the rock shaft 32. From the foregoing it is obvious that rotation of the cam disk 47, through the operation of the escapement and motor device, rocks the shaft 32 as a result of each depression of each numeral key and thereby raises the levers 29 and 31, which, in turn, raise the frame 27. Springs 50 (Figs. 2 and 3) are effective to restore the levers 29 and 31 and the other parts directly movable therewith to their idle or normal positions. The frame 16 supports a plate 51 at each end, each of said plates being provided with a series of vertical slots 51^a, which correspond in number and relative position to the rows of pins 21. A number of plates 52 (Figs. 2 and 11) have their ends extending through the slots 51^a at opposite ends of the frame 16. There is one of these plates 52 for each row of pins 21, and said plates are positioned adjacent to the lower ends of the pins. Each plate 52 supports a series of pawls 53. A suitable form and arrangement of the pawls 53 is illustrated in Fig. 11, in which the pawls are shown as extending above and below the plates 52, and the pawls of each series are 130

provided with pins 54 near their lower ends extending across the front edges of the corresponding pins 21 of the adjacent lower order. A small spring 55 connects each 5 pawl to its supporting plate 52 and is effective to hold the pin 54 thereon in contact with the edge of the corresponding pin 21. Each pin 21 is formed with an oblique shoulder 56 which rubs against the contact- 10 shoring pin 54 when said pin 21 is raised, thereby rocking the pawl 53 against the tension of its spring 55 and positioning a pin 57 at the upper end of said pawl 53 in a notch or seat 58 of the pin 21 of corresponding value 15 in the adjacent row. There is one series of pawls 53 for each numerical row or order of pins 21, so that when a pin 21 in any row is raised said pin 21 sets the corresponding pawl 53 in engagement with the adjacent pin 21 of corresponding value. The notches or seats 58 in which the pins 57 become engaged as aforesaid, constitute latches to retain the pawls 53, the latching engagement being effected by a slight upward and down- 20 ward movement of the pin 21 so engaged in order to seat the pin 57 within the notch 58.

From the foregoing it will be understood that depression of any numeral key first sets 30 a pin 21 of corresponding value in the additional row of pins indicated by X. The motor and escapement device which operate as an incident to the operation of a numeral key, rocks the shaft 32 as previously described and raises the basket or frame 27. As above explained the pin 21 in the row X, which is set by the numeral key, engages a pawl 53 with a pin 21 of corresponding value in the next adjacent row which, in 35 this instance, is units row. Therefore, when the basket or frame 27 is raised the plates 52 will also be raised, and the pawl 53 which had been adjusted in engagement with one of the pins 21, will raise said pin 21 until the 40 said pin 21 is latched upon the corresponding latch pin 24. The frame or basket 27 supports two plates 59 which are longitudinally movable in slots 60 in the sides of said frame or basket. The ends of the plates 52 45 project through the slots 51 and over the plates 59 so that when the basket 27 is raised by operation of the motor device the plates 52 will also be raised and thereby control the pins 21. The plates 59 are pivotally connected to the carriage 9, and are moved in 50 unison with said carriage to perform certain classes of work as hereinafter explained. When the pin in units row is raised in this manner said pin also positions a pawl 53 of 55 corresponding value so that subsequent operation of a numeral key will cause the motor to operate and permit movement of a pin in tens row of corresponding value to the previously positioned pin in units row, and this 60 operation will be maintained throughout the 65 series of rows of pins as the numeral keys are operated. When a pin 21 in any row is raised after another pin in that row has been raised, the adjustment of the second pin moves the plate 23 so that the previously set 70 pin will be restored to its idle position by its spring 22.

In the machine illustrated the type-carriers 61 are arcuate in form and are suspended from a shaft 62 (Figs. 2 and 3).⁷⁵ The type-carriers are associated with racks 63 which are also suspended from the shaft 62 and which have pin-and-slot connection 64 with the type-carriers. The racks are connected with rearwardly extended arms of the type-carriers by springs 65 which constitute an elastic connection between the type-carriers and racks. The main rock-shaft 66 has connections 67 leading to arms 68 which are pivoted upon the shaft 62 and 80 which support a rod 69 extending transversely in front of the vertical arms of the type-carriers and racks. Rearwardly extended portions of the arms 68 support a rod 70 which is connected to the rearwardly ex-⁸⁵ tended portions of the type-carriers by springs 71. When the shaft 66 is rocked forwardly the arms 68 carry the rods 69 forwardly away from the vertical portions of the type-carriers and racks and also extend 90 the springs 71 effectively to actuate forwardly the type-carriers and associated racks which are permitted to operate. This operation of the type-carriers and racks is substantially the same as the operation of the type-⁹⁵ carriers and racks in the machine of the Hubert Hopkins Patent #1,039,130, of September 24, 1912.

Each rack has a pivoted heel 72 which is arranged to operate within the channels 105 formed by the guides 20 and to engage in pins 21 which may have been set up to represent numbers as hereinbefore explained. The engagement of the heels 72 with the pins 21 stops the movement of the type-carriers and racks and aligns the printing type 73 adjacent to the printing line of paper, supported upon a platen 74. Printing is effected by the action of the type-driving hammers 75, through connections operated 110 incidentally to the operation of the type-carriers, and substantially in the manner described in the Hopkins patent aforesaid. After the numbers are printed the type-carriers and racks are returned to idle position 115 by the rod 69 which is moved rearwardly by the return rocking movement of the shaft 66 which is effected automatically by power springs 76. The usual adding wheels 77 are controlled and operated by the racks 63 120 effectively to add the numbers listed or printed, in the well understood manner, substantially as described in the Hopkins patent.

After the number has been recorded by 130

the operation of the type-carriers and type-driving hammers the pins 21 which had been set to represent the number recorded may be automatically returned to their idle or initial positions, or may be retained in position to represent the number to be repeated, as in multiplication, for instance. An arm 78, (Figs. 3 and 18), is attached on the rock-shaft 66, and has a pin 79 extending under a link 80. The rear end of the link 80 is connected to a lever 81, which is supported by a shaft 82. The link 80 is actuated toward the side of the arm 78 by a spring 83 connecting the lever 81 and link 80. The lever 81 has a rearwardly extending arm to which is pivoted a link 84 and which is supported by pins 85, (Fig. 14), on the rear standards 17, said pins 85 passing through slots 86 in said link. The link 84 is provided with two arms 87 having inclined or oblique upper edges adapted to operate against rollers 88 on a vertically movable member 89 supported by and having pin-and-slot connection 90 with the rear standards 17. The member 89 is actuated downwardly by springs 91. Two arms 92 attached to a rock shaft 174 extend under said member 89. The member 89 extends transversely under the lower ends of the rear transverse row of pins 21. The rear transverse row of said pins 21, as previously explained, correspond to the numeral character "0." When said member 89 is raised by the lateral movement of the cam members 87, or otherwise, said member 89 will raise all of the "0" pins 21, that is, all of the pins 21 in the rear transverse row, and simultaneously release and enable the remaining pins 21 to be pressed downwardly by their springs 22. It will be understood that this operation is effected by movement of the link 80, and I will now describe the device for operating the said link 80 as an incident to the recording or adding of a number, so that the pins 21 which had been set to represent said numbers will be automatically restored to idle position, thereby clearing the pin frame. A pawl 94, (Figs. 3 and 18), is pivoted upon the link 80 and has a hook 95 on its forward end in position to be engaged by the pin 79. A spring 96 yieldingly holds the hook 94 upon the pin 79. The arrangement is such that, after the heels 72 have engaged the proper pins 21 which had been set to represent the number to be added, the pin 79 will have moved the connections including the link 80, lever 81, and link 84, and the other parts actuated by said link 84, a sufficient distance to raise the member 89 effectively to raise the "0" pins 21, and thereby permit the remaining pins to be pressed downwardly by their springs 22.

The pins 21 representing the number with which the heels 72 had been engaged in the adding or recording operation, are thus re-

stored to their idle or initial positions before the type-carriers and racks begin their return movements. Therefore, it is necessary to prevent additional forward movement of said type-carriers and racks, which would otherwise occur. For this reason suitable restoring devices are provided and are co-operatively related to the type-carriers, and particular reference may be made to Figs. 2, 3 and 25 for a clearer understanding of said devices. A rock shaft 97 is supported transversely above the arcs of the type-carriers. A lever 98 which extends above and below said rock shaft is attached to one end of said shaft, and an arm 99 corresponding to the upper portion of said lever is attached to the opposite end of said shaft, and a rod 100 is attached between the upper ends of said arm and lever. For each of the type-carriers there is a corresponding pawl 101 mounted upon the shaft 97 and having their lower ends normally above and out of contact with the upper edges of the type-carriers. Each type-carrier is formed with ten projecting teeth 102, (Figs. 2 and 3), corresponding in engagement to the engagement of the type and to the arrangement of the pins 21, so that, as in each numerical row of pins 21 there is one pin for each of the ten numeral characters, and, as in the case of the type 73 there is one type on each type-carrier for each of the ten numeral characters; so, in the case of the teeth 102, there are ten teeth on each type-carrier, being one for each of the ten numeral characters or figures.

The upper end of each of the pawls 101 engages in front of the rod 100, so that, in one position of said rod 100, all of the pawls will be held out of engagement with the type-carriers; whereas, in another adjustment of said rod 100 all of the pawls will become engaged with the type-carriers, said pawls being actuated toward the type-carriers by springs 103. The rod 100 has detent springs 104 connected thereto and in idle position of the machine engaged in front of projections 105 effectively to hold the rod 100 in position to prevent engagement of the pawls 101 with the type-carriers. Movement of the rod 100 to engage the detent springs 104 behind the projections 105 permits the pawls 101 to engage the teeth 102 on the type-carriers, and this adjustment is automatically effected before the pins 21, representing the number being recorded and added, are restored to idle position. A link 106 is supported by a pin-and-slot device 107 and has its front end pivotally connected to the lower end of the lever 98, and is formed with a lateral extension 108 at its rear end, and is formed with an upward extension 109 near its front end. The lever 68 which operates adjacent to the link 106 has a lateral projection 110

which, in the idle or "rest" position of said lever 68 of the machine, engages the projection 108. During forward movement of the lever 68, which occurs during each adding or recording operation, the projection 110 engages the projection 109 and actuates the link 106 forwardly, thereby moving the rod 100 rearwardly and engaging the detent springs 104 behind the projections 105, and 10 permitting the pawl-actuating springs 103 to engage all of the pawls 101 with teeth on the type-carriers. The operation of the parts is so timed that the pawls 101 become engaged with the type-carriers in this manner before the pins 21, representing the number being recorded and added, are restored to idle position. Therefore, the type-carriers and racks will be prevented from further movement and, upon return movement 20 of the parts, the projection 110 engages the projection 108 and operates the rod 100 effectively to raise and disengage all of the pawls 101 from the type-carriers, and also to engage the detent springs 104 in front 25 of the projections 105, thereby latching the pawls in disengaged adjustment.

As previously explained, the heels 72 are pivoted upon the racks 63, so that when said racks are restored to their idle positions 30 said heels 72 are raised as they pass rearwardly over the upraised "0" pins until said heels pass behind said pins. Springs 111 connect rearwardly extended ends of the heels 72 with projections on the racks effectively to actuate the front ends of the heels 35 downwardly and to cause said heels to operate within the channels formed by the guides 20. A pin 112 on each rack extends through a slot in the corresponding heel 72, limiting 40 the movement of said heel.

Suitable connections are provided whereby the adding and recording mechanism may be coöperated in order to clear the adding mechanism and to record any total represented therein. Said connections include a key 113 which is pivoted upon the front end of a lever 114 mounted at 116, (Fig. 3). The rear end of the lever 114 is in pivoted engagement with a lever 117 supported at 50 118 and having an upwardly extended arm, to the upper end of which a link 119 is pivoted. The rear end of the link 119 is connected to an arm 120 attached to a rock shaft 121. Two arms 122 on the rock shaft 121 extend forwardly toward the racks 63 and support a rod 123 across and over the rear ends of the heels 72, so that, when the key 113 is depressed, the connections from 55 said key 113 will rock the shaft 121 and 60 raise the front ends of the heels 72 above the upper ends of the "0" pins 21 and permit forward movement of the racks and type-carriers, as required to record the total represented in the adding mechanism 77 and 65 to clear said mechanism. The construction

and coöperation of the adding wheels and racks as required to enable them to coöperate in these clearing operations are well understood and do not require specific description herein. In order to retain the adding 70 wheels in mesh with the racks in clearing operations a rear arm of the lever 117 has a link 124 leading to a link 125 which connects to the frame 126 which is operable effectively to raise and lower the adding 75 mechanism in the usual manner.

In the machine illustrated, after the numbers have been printed an additional operation of the main rock shaft 66 and its connections is necessary in order to complete 80 the carrying or transferring operation and restore the racks 63 to idle position. Since this is necessary, it is desirable to prevent operation of the key 113 before the parts have completed their operation and function. The end of the shaft 32 has an arm 126 attached thereto and having pin-and-slot connection with a lever 127, (Fig. 3), whose front end is connected with a pivotally supported arm 128. Since the shaft 90 32 is rocked by the motor and escapement device as an incident to the setting up of each number, the link 127 will be actuated forwardly by the arm 126 and will be retained in its forward adjustment by a detent device 129 of well understood construction. When in its forward adjustment the upper end of the member 128 is under a pin 130 on a link 131 whose lower end is connected to the lever 117. The member 128 95 in such adjustment prevents movement of the link 131 and thereby prevents depression of the total key 113 until said member 128 has been moved away from the path of movement of the pin 130. The lower edge 100 of the link 127 is formed with two shoulders 131. A lever 132 supports a pawl 133 and is actuated forwardly by a spring 134. About the time that the shaft 66 completes 105 its forward rocking movement an arm 135 110 on said shaft engages the projecting end of the lever 132 and thereby operates said lever. The pawl 133 is thereby engaged with the rear projection 131 and moves the link 127 and the member 128 a part of the 115 distance toward their idle position. Should the numeral keys be operated to set up another number before the rock shaft 66 is again operated the link 127 again will be moved forward so that, as is obvious, a 120 forward rocking of the shaft 66 is necessary after the last number has been added or listed before the link 127 and the member 128 will be restored to idle position, and before the key 113 may be operated for total 125 printing or clearing operations.

On some occasions it is desirable to add or list the same number more than once, or to change the number in decimal relation, as in multiplication. On such occasions it is 130

desirable to prevent cancellation of the number set up, and it is desirable that the pins 21, representing the number, be retained in their adjusted position to enable the adding and recording mechanisms to be successively or repeatedly operated as required to add or record the number repeatedly. For this purpose I have provided repeat mechanism which prevents effective operation of the pin restoring devices, and permits the adding and recording mechanisms to be operated without restoring the pins 21 to their idle positions. A repeat key 136 is pivoted to one arm of a bell-crank lever 137, (Fig. 3) whose opposite arm is connected to a link 138, the rear end of said link being connected to a pivoted support 139, (Figs. 3 and 18). A pin 140 on the link extends behind the lower end of the hook member 94—95, so that depression of the repeat key will operate the parts to raise the hook 95 above the path of movement of the pin 79. This permits repeated operation of the pin 79 and of the recording and adding mechanisms without operation of the pin restoring devices which are actuated by the member 94 and the pin 79 as hereinbefore explained. To prevent the link 127 from being restored to idle position by two operations of the rock shaft 66 when numbers are being repeated, the link 138 is provided with a projection 141 which extends alongside of the link 127. When the link 138 is moved forwardly by depression of the repeat key 136 the projection 141 assumes a position at the side of the two projections 131 and prevents the pawl 133 which is wider than the edge of the link 127 and which extends under the position occupied by the projections 141 from engaging the projections 131. In other words, when the lever 132 is operated by the arm 135 in the rocking of the shaft 66 the pawl 133 is prevented from engaging the projections 131 because said pawl 133 rubs against the lower edge of the projection 141 and is thereby prevented from engaging said projections 131. Obviously, therefore, an additional stroke or operation of the main rock shaft 66 will be required after the item has been repeated for the last time before the key 113 can be operated to position the parts for clearing operations.

Occasions arise in which it is desirable to list and add two or more columns of numbers simultaneously. My machine is equipped with mechanism whereby the operator is enabled, at will, to adjust the machine so that the machine may be operated to list and add parallel columns of numbers simultaneously. The adjusting mechanism is best illustrated in Figs. 4, 15, 16 and 18. A lever 142 has a link 143 extending behind the frame 16 and connected to a lever 143^a which has one end pivoted to a stationary

support and the other end pivoted to the carriage 9. It is obvious that operation of the lever 142 will move the carriage leftwardly, and that such movement of the carriage moves the levers 13 to position the hammers 15 under some other row of the pins 21. When so positioned the levers 13 may be operated by the numeral keys to set up a number in the pin frame in higher orders or in a column in the left-hand side of the pin frame, the pins 21 acting, as previously described, in connection with the devices for setting of numbers. A lever 145, pivotally mounted intermediate of its ends has its rear end connected to the lever 142 and its front end connected to the lever 146 pivotally supported at 147, and provided with an actuating spring 148. When the carriage 9 moves to the left as required before a number can be set up in the pin frame in another column therein while a previously set number remains set up in one column, the plates 59 are also moved to the left. Leftward movement of the plates 59 positions a narrow part thereof under the projecting ends of the members 52 at the right. As shown in Figs. 12 and 21, the plates 59 are formed with a wide portion which is under the projecting ends of all of the members 52 when the carriage 9 is at the right, so that all of said members 52 will be raised when the basket or frame 27 is raised and the carriage 9 is at the right. However, when the carriage 9 is moved to the left as required to position the hammers 15 of the levers 13 under a row of stops 21 in a higher numerical order preliminary to setting a number in another column, the wide portions of the plates 59 are moved to the left and narrow portions of said plates are positioned under the ends of the members 52 which are at the right of the row of pins 21 against which the hammers 15 are positioned to act. In other words the plates 59 will not raise the members 52 in any orders at the right of the row of pins above the hammers 15, so that the number which had previously been set up at the right of the frame 16 will not be disturbed by the setting of another number at the left of said frame. The numbers having thus been set in parallel and separated columns in the frame 16 may be simultaneously recorded in parallel columns by operation of the recording mechanism in the usual way. The repeat mechanism may also be adjusted to prevent elimination or cancellation of the numbers from the pin frame as would occur should the repeat mechanism not be adjusted. The repeat mechanism operates in the same manner when numbers are repeated in parallel columns as it acts when a single number is being repeated.

The lever 146 may be set or operated to

position the carriage 9 for parallel column work in any suitable manner and may be held by any suitable devices. When numbers are printed or listed in parallel columns it is desirable to prevent the printing of intermediate ciphers between the two columns of numbers. For interrupting the co-operative action between the printing mechanism in the higher orders and the printing mechanism in lower orders any suitable devices may be utilized. I have illustrated a known form of device (Figs. 15, 16 and 17) consisting of sliding plates 149 movably supported upon the bars 150 which are connected to the latch pawls 151 engaging the type-driving hammers 75. As usual in listing the numbers the type-carriers act upon levers 152 effectively to raise the rear ends of the bars 150 into the path of movement of a swinging bail 153 carried between arms attached to a rock shaft 154. The bars 150 are provided with the usual projections 155 whereby the raising of a bar in a higher order will raise all bars in lower orders. The projections 155 extend under the sliding plates 149 in one position of said plates so that when one bar 150 is raised it will raise the adjacent bar in a lower order by engagement of the projections 155 under the sliding plate 149. The sliding plates 149 are movable to position such that the projections 155 will not engage the lower edges of said plates and when so positioned that the projections 155 do not engage the said plates 149, the printing of ciphers at the right of a number will be prevented. For manipulative purposes the sliding plates are provided with extensions 156, so that by pressing the finger against the extensions 156 the sliding plates 149 may be forced inwardly to such position that the projections 155 will not engage therewith. Each sliding plate is provided with a detent spring 157 engaging in notches in the upper edge of the bars 150 in which it is mounted and constituting a latch to hold the sliding plate in its different adjustments. As shown in Fig. 16 the projecting portions 156 are provided with type indicating the numerical orders thereof, respectively. In the specific embodiment shown there are nine numerical orders in the machine but it is obvious that the number of numerical orders may be increased simply by duplicating the mechanism which I have described so as to provide additional numerical orders in the machine. Of course, I do not restrict myself to a machine containing any specific number of numerical orders since it is well known that machines having varied numbers of numerical orders are required commercially and may be produced without the exercise of the invention, simply by changing the number of trains of adding and recording mechanisms and their associated parts. The upper end of the lever

146 supports two escapement elements, one of which is designated by 157, and the other of which is designated by 158 and which are actuated toward each other by a connecting spring 159, their movement being limited by a pin 160. A spring 161 connects the upper member 157 with the lever 146 and actuates both of said escapement members downwardly. A sliding link 162 supported by a pin-in-slot device 163 has a pin 164 under the member 157 and the lower end of said link is connected to a lever 165. The front end of the lever 165 is connected to a key 166, so that operation of said key 166 will raise the link 162 and the escapement member 157.

In adjusting the machine for multiple column work of the character previously described, the sliding plate 149 in the order at the right of the left-hand column is pressed inwardly and latched so that the printing of ciphers between the left hand column and the right hand column of numbers will be prevented. The projecting part 156 is provided with escapement abutment 167 which, when moved inwardly to split the machine, that is, to prevent the printing of ciphers between two columns, occupies a position in which it may be engaged by the end of the escapement member 157 and thereby hold the lever 146 in position to retain the carriage 9 with the lever hammers 15 under a row of pins 21 in a higher order for setting a number at the left of the pin frame. A satisfactory operation of the machine consists in first setting a number in the column at the right of the pin frame and then adjusting the carriage 9 and levers 13 to position, to set up a number at the left of the pin frame. This adjustment of the carriage 9 and levers 13 involves a movement of the lever 146. The lever 146 is provided with a handle 168 which extends through a slot 169 in the case of the machine and which constitutes means for manipulating said lever 146 to move the carriage 9 toward its initial position at the right as, for instance, when error has been made in striking any of the numeral keys.

The upper end of the lever 146 is provided with type 146 which constitutes a visible indication of the position of the carriage 9 and of the lever 146 so that the operator may be informed at all times whether or not the machine is adjusted for multiple column work, and, for what columns the machine is adjusted.

Assuming that it is desired to divide the machine into two columns in which the seventh, eighth and ninth numerical orders will be utilized as one column, and a number of the lower numerical orders will be utilized for the other column, the adjustment will be effected as follows: Press inwardly the key 156 in the seventh numerical order, 160

thereby moving the coupling 149 in the seventh order out of position to coöperate with the release bar 150 in the eighth order, thereby preventing the printing of ciphers to the right. Then depress the key 166 which raises the link 162, and thereby raises the member 157, (Fig. 16), and releases the hook on the end of the member 157 from the projection 167 in the lowest numerical order. The spring 148 then acts to move the member 146 to the left, until further movement is stopped by engagement of the hook 158 with the abutment 167 in the seventh numerical order, which had been pressed inwardly, as above explained. This action of the member 146 also moves the carriage 9, (Fig. 9), and positions the projections 15 under the pins 21 in the seventh numerical order, so that operation of the numeral keys will result in setting of the pins in the seventh numerical order, and subsequent operations of the numeral keys will result in successively setting the pins in higher numerical orders. This permits the machine to be operated for one column of work in the seventh and higher numerical orders, and by restoring the carriage 9 to its normal position the machine can be utilized for performing a separate column of work in lower numerical orders.

In event of error on the part of the operator in striking the wrong numeral keys and thereby setting up the wrong number in the differential mechanism, the pins in the differential mechanism may be restored to idle position and the erroneous number canceled or erased from the differential mechanism before being recorded or added and independently of any operation of the adding or recording mechanism. The error correcting or correction key 170 is pivotally supported by a bell-crank lever 171 (Fig. 5) which is operatively connected with a link 172, the rear end of which is connected to an arm 173 on a rock shaft 174. The two arms 92 which are attached to the rock shaft 174 extend under member 89. Therefore, depression of the key 170 results in raising the member 89 effectively to set up all "0" pins 21 to permit any other pins which had previously been set up to be returned to their idle or initial positions. Thus any number may be canceled or erased from the differential mechanism independently of any operation of the adding or recording mechanisms so that any error in striking the numeral keys need not enter into the examples or work performed by the machine.

From the preceding description it will be understood that the power stored within the motor is utilized as the numeral keys are operated, and that since the power is utilized it is necessary to rewind the motor spring 45 in some manner in order to maintain the necessary power in the motor. The

motor is automatically rewound by the operation of the main rocking shaft 66 with which the motor-spring drum 44 is entrained. A ratchet wheel 176 (Figs. 4, 7 and 12) is attached to the sleeve 46 to which, 70 it will be remembered, one end of the motor spring 45 is attached. A disk 177 is loosely mounted on the sleeve 46 at the side of the ratchet wheel 176 and supports a pawl 178 which is actuated into engagement with the ratchet wheel 176 by a spring 179 so that, when the disk 177 is turned in one direction the pawl 178 will rotate the ratchet wheel 176 and wind the motor spring. A detent pawl 180 mounted on a stationary support 80 181 engages the ratchet wheel 176 and prevents movement of said ratchet wheel in a direction to unwind the motor spring 45. A segmental rack 182 is pivotally connected to the rock shaft 66 and meshes with a pinion 85 183 rigid with the disk 177. It is obvious that reciprocation of the rack 182 will actuate the pinion 183 and the pawl 178 effectively to wind the motor spring 45, and that said rack and pinion and pawl may be returned to their initial positions because the pawl 178 will ride forwardly over the teeth of the ratchet wheel 176 while said ratchet wheel is held from turning with said pawl 178 by means of the pawl 180. An arm 184 90 is attached to the rock shaft 66 at the side of the rack 182. The rack 182 is provided with an inclined and angular slot 185 through which extends a short rod 186 which is actuated downwardly and held normally seated in the lower end of the slot 185 by springs 187 which connect said rod with the rack. The arm 184 extends under a roller 188 mounted on the rod 186. The parts are so adjusted and arranged that when the 95 shaft 66 is rocked the arm 184, by engaging the roller 188 on the rod 186, actuates the rack 182 effectively to wind the motor spring 45. When the motor spring is wound tight enough it will overcome the power of 100 the springs 187 and on further rocking of the shaft 66 the arm 184 will raise the rod 186 within the slot 185 without actuating the rack 182. Therefore, there is no danger of breaking the motor spring 45 by winding it beyond its strength because the winding devices give way and yield before the superior tension and strength of the spring 45, when said spring has sufficient power stored therein.

It would appear that frequent and successive operation of the numeral keys for a number of times considerably in excess of the capacity of the machine, without operating the rock shaft 66, will release the tension 120 in the spring 45, so that, when it is desired to set up a number to be added or listed, there will not be sufficient power in the spring 45 to actuate the pin setting devices in the differential mechanism. Such abnor- 130

mal and undesired operation is automatically prevented by the motor itself which, at a time prior to exhausting of the power of the spring 45, locks the numeral keys and renders it impossible to operate the keys without first rocking the shaft 66 to store up the necessary power in the motor spring 45. Numeral key levers 2 operate in notches in the comb plate 189 (Fig. 6). Depression of any numeral key moves laterally the cam shaped key-locking plates 190 effectively to lock all remaining numeral keys until the key depressed returns to its idle position. Therefore, if the locking plates 190 be locked against movement it will be impossible to depress any of the numeral keys. A sliding plate 191 is supported by pin-in-slot devices 192 and is provided with a projection 193 adapted to be pressed against the locking plate 190 at the end of the series and thereby lock all of the numeral keys. Normally the sliding plate 191 is actuated to hold the projection 193 away from the locking plates by means of a spring 194 connecting a pin on the sliding plate with one of the pins which support said plate. A movable bar 195 is mounted in guides 196 and extends over a projecting end of the sliding plate 191. The bar 195 carries a cam 197 which, on forward movement of said bar engages the projection 193 and moves the locking plate 191 to press said projection 193 against the locking plate 190 at the end of the series, to lock all of the numeral keys. The bar 195 is capable of a number of stepping movements and is provided with a number of notches 198 (Fig. 13) adapted to engage a notched guide 199 to retain the bar 195 in its different adjustments. The motor-spring drum has a projection 200 which, in successive revolutions of the motor-spring drum engages teeth 201 on the bar 195 and actuates said bar forwardly one step at each revolution of said drum. A spring 202 connected to the guide piece 199 and extending over the bar 195 prevents displacement of said bar. From the foregoing it will be understood that as the power is released from the motor spring 45 by operation of the numeral keys the bar 195 is advanced to a position to lock the numeral keys. Before the power is exhausted from the spring 45 the bar 195 will have been advanced a sufficient distance to lock and prevent further operation of the numeral keys. Under these conditions one or more operations of the rock shaft 66 will be required before any number can be set up in the machine and the rocking of the shaft 66 in addition to storing power in the motor spring 45 will also actuate the bar 195 rearwardly and release the numeral keys. The rock shaft 66 carries a depending arm 203 supporting an actuating pawl 204 yieldingly sustained by a spring 205. The under side of the bar 195 is formed with a number of

teeth 206 which, in an advanced position of the bar 195, will be engaged by the pawl 204 when the shaft 66 is rocked to store power in the motor spring 45. The engagement is such that the movement of the arm 203 and the pawl 204 will actuate the bar 195 rearwardly to restore said bar to its idle adjustment and permit operation of the numeral keys after the power has been stored within the motor spring 45. 75

I have shown a handle 207 attached to the rock shaft 66 as a convenient means of rocking said shaft in one direction. It will be understood, however, that I do not restrict myself to a hand operated machine and that 80 the machine may be operated by any of the suitable power driving mechanisms available for such purpose.

I do not restrict myself to specific forms of devices nor to an embodiment of my invention in the machine of any specific capacity. 85

What I claim and desire to secure by Letters Patent is:

1. In an adding machine, differential 90 mechanism for controlling adding mechanism and comprising a number of movable parts arranged in numerical orders and adapted to be set to represent numbers, manual means for setting the parts in units order to represent the digits of numbers, and means under the control of said part in different orders for setting parts of corresponding value in adjacent orders incidentally to subsequent setting of another part 100 in units order.

2. In an adding machine, the combination of a number of movable parts arranged in numerical orders and adapted to be set to represent numbers, manual means for setting the parts in units order to represent numbers, means under the control of a part in units order for setting a part of corresponding value in an adjacent order incidentally to subsequent setting of another part in units order, elements for holding the parts in the positions in which they are set, and manual means for releasing said elements. 110

3. In an adding machine, the combination of a number of movable parts arranged in numerical orders and adapted to be set to represent numbers, manual means for setting the parts in units order to represent numbers, means under the control of a part in each order for setting a part of corresponding value in an adjacent order incidentally to subsequent setting of another part in units order, releasable elements for holding the parts in the positions in which they are set, an actuator for releasing said elements, and automatic means for operating said actuator. 115

4. In an adding machine, differential mechanism for controlling adding mechanism, comprising a number of movable parts arranged in numerical orders and adapted 120

- to be set to represent numbers, manual means for setting the parts in units order to represent numbers, means under the control of a part in each order for setting a part of corresponding value in an adjacent order incidentally to subsequent setting of another part in units order, releasable elements for holding the parts in the positions in which they are set, actuating devices for releasing said elements, a rock shaft for operating said actuating devices to release said elements, and additional manual means for operating said actuating devices independently of said rock shaft.
15. 5. In an adding machine, a number of movable parts arranged in numerical orders and adapted to be set to represent numbers, means for setting the parts in units order successively to represent the digits of numbers, and means under the control of the parts in said units order for setting parts of corresponding value in an adjacent order incidentally to subsequent setting of the same or other parts in units order.
20. 6. In an adding machine, series of movable parts arranged in numerical orders adapted to be set to represent numbers, actuators for the series of parts in units order, numeral keys for operating said actuators to set successively and selectively the parts in units order, and means under control of the parts set as aforesaid for setting parts of corresponding value in adjacent orders incidentally to subsequent operation of any of said numeral keys.
25. 7. In an adding machine, movable parts arranged in rows and said rows arranged in numerical orders, manipulative devices for setting the parts in units row selectively and successively to represent the digits of numbers, means under control of said parts for setting parts of corresponding value in adjacent orders incidentally to subsequent operation of said manipulative devices to set parts in units row, and an actuator for moving to its idle position each of said parts when another part in the same row is set to represent a digit.
30. 8. In an adding machine, a number of rows of movable parts, said rows being arranged in numerical orders, numeral keys and co-operating motor mechanism for setting the parts in units order selectively and successively to represent the digits of numbers, and means under the control of the numbers in said units order for setting parts of corresponding value in an adjacent order incidentally to subsequent operation of said numeral key and motor mechanism.
35. 9. In an adding machine, a number of movable parts arranged in rows in numerical orders and adapted to be set to represent numbers, manipulative devices for setting the parts in one order to represent the digits of numbers, means under control of the parts in said order for setting parts of corresponding value in adjacent orders incidentally to subsequent operation of another part in the first order, and a motor controlled by said key mechanism and arranged to operate said means.
10. In an adding machine, a number of movable parts arranged in rows in numerical orders and adapted to be set to represent numbers, manipulative mechanism for setting the parts in one order to represent the digits of numbers, means under control of the parts in said order for setting parts of corresponding value in an adjacent order incidentally to subsequent operation of a part in the first order, a motor controlled by said mechanism and arranged to operate said optionally operable means, and means for restoring said parts to idle position.
11. A number of movable parts arranged in rows in numerical orders and adapted to be set to represent numbers, manipulative mechanism for setting the parts in units order to represent the digits of the numbers, means under control of the parts in said units order for successively setting parts of corresponding value in an adjacent order incidentally to subsequent operation of a part in units order, and means under control of said parts in adjacent orders for successively setting the necessary parts to represent the digits of numbers toward higher numerical orders incidentally to subsequent operation of a part in said units order.
12. The combination of a number of rows of movable parts arranged in numerical orders and being adapted to be set to represent numbers, manipulative mechanism for setting the parts in one order to represent the digits of numbers, means under control of the parts in said order for successively setting parts of corresponding value in an adjacent order incidentally to subsequent setting of a part in the first order, means under control of said parts in adjacent orders for successively setting the necessary parts toward higher orders to represent the digits of numbers incidentally to subsequent operation of a part in said first order, automatic mechanism for operating said two last-named means, supports for holding said parts in the positions in which they are set as aforesaid, a series of reciprocating elements limited in their movements in one direction by the parts which are set as aforesaid, an actuator for moving said elements toward idle position after they have been limited by said parts, and means actuated by said actuator for releasing said parts.
13. The combination of a number of movable parts arranged in rows in numerical orders and being adapted to be set to represent numbers, mechanism for selectively setting the parts in one order successively to represent the digits of numbers, means

under control of the parts in said order for successively setting parts of corresponding value in an adjacent order incidentally to subsequent setting of a part in the first order, means under control of said parts in adjacent orders for successively setting the necessary parts in higher orders to represent the digits of numbers incidentally to subsequent setting of a part in said first order by said mechanism, supports for holding said parts in the positions in which they are set as aforesaid, an actuator under control of said mechanism arranged to operate said means; a rock shaft, means for rocking said shaft, and means actuated by said rock shaft for releasing said parts from said supports.

14. The combination of a number of movable parts arranged in rows in numerical orders and being adapted to be set to represent numbers, mechanism for selectively setting the parts in one order successively to represent the digits of numbers, means under control of the parts in said order for successively setting parts of corresponding value in an adjacent order incidentally to subsequent setting of a part in the first order, releasable supports for holding said parts in the positions in which they are set as aforesaid, an actuating device, means under control of said actuating device for releasing said parts from said supports, and optionally operable mechanism adjustable to prevent release of said parts when said actuating device operates.

15. In an adding machine, a number of parts arranged in rows in numerical orders and adapted to be set to represent numbers, manipulative mechanism for setting the parts in units order successively to represent the digits of numbers, an actuating device controlled by said mechanism for setting parts of corresponding value to the parts set by said mechanism incidentally to subsequent operation of said mechanism, and means for restoring said parts to idle position.

16. The combination with a number of movable parts arranged in numerical orders and adapted to be set to represent numbers, and means for setting the parts in units order to represent the digits of numbers successively, of means under the control of a part in units order for setting a part of corresponding value in an adjacent order incidentally to subsequent setting of another part in units order.

17. The combination with a number of movable parts arranged in numerical orders and adapted to be set to represent numbers, and manual means for setting the parts in units order to represent numbers, of means under the control of the parts in the several orders for setting parts of corresponding value in adjacent orders incidentally to

subsequent operation of said manual means to set parts in units order.

18. In an adding machine, the combination of a series of type-carriers, mechanism for actuating said type-carriers to differential positions, racks connected with and movable relative to said type-carriers and movable by said type-carriers to the differential positions of said type-carriers, differential mechanism controlling the movements of said racks and type-carriers, a rod for actuating said type-carriers and racks to their starting points, a shaft supported transversely of said type-carriers, pawls mounted on said shaft, springs actuating said pawls toward said type-carriers, means holding said pawls out of engagement with said type-carriers during movement of said type-carriers to the differential positions aforesaid, means for engaging said pawls with said type-carriers after each differential operation of said type-carriers while the type-carriers are in their differential positions, adding mechanism movable into engagement with said racks after said pawls have engaged said type-carriers, and mechanism for actuating said rod to restore said type-carriers and racks to their starting points and causing said racks to actuate said adding mechanism.

19. In an adding machine, the combination of a series of type-carriers, mechanism for actuating said type-carriers to differential positions for movement therefrom to operate adding mechanism in adding operations, racks connected with and movable relative to said type-carriers and movable by said type-carriers to the differential positions mentioned and from the differential positions to operate the adding mechanism in adding operations, differential mechanism controlling the movements of said racks and type-carriers to the differential positions, a rod for actuating said type-carriers and racks from said differential positions to their starting points, a shaft supported transversely of said type-carriers, pawls mounted on said shaft, means holding said pawls out of engagement with the type-carriers during movement of the latter to the differential positions aforesaid, means for engaging said pawls with said type-carriers after said type-carriers have stopped in the differential positions mentioned, adding mechanism movable into engagement with said racks after said pawls have engaged said type-carriers, and mechanism for actuating said rod to restore said type-carriers and racks to their starting points and to cause said racks to actuate said adding mechanism.

20. In an adding machine, the combination of a series of type-carriers, mechanism for actuating said type-carriers to selected differential positions, racks connected with

- and movable relative to said type-carriers and movable by the type-carriers to the differential positions mentioned, and movable from the differential positions in adding operations, differential mechanism limiting the movements of said racks and type-carriers, a rod for actuating the type-carriers and racks to their starting points, a series of pawls movable to position to hold said type-carriers after said type-carriers have stopped in their differential positions, means for moving said rod to actuate said type-carriers and racks to their starting points after each differential operation thereof and while said pawls are in position to prevent movement of any of said type-carriers toward said rod, adding mechanism, and means for moving said adding mechanism into engagement with said racks after said type-carriers and racks have stopped in their differential positions and after said pawls have been moved to position to prevent further differential movement of said type-carriers.
21. In an adding machine, the combination of a series of type-carriers, mechanism for actuating said type-carriers to differential positions, racks connected with and movable relative to said type-carriers and movable by said type-carriers to the differential positions of said type-carriers, differential mechanism limiting the movements of said racks and type-carriers, a series of pawls for preventing further differential movement of said type-carriers and racks when said differential mechanism is disengaged therefrom, mechanism for moving said pawls to position to prevent further differential movement of said type-carriers and for disengaging said differential mechanism from said racks, adding mechanism, means for engaging said adding mechanism with said racks after said pawls have been moved to position to prevent movement of said racks and type-carriers, a rod, and means for operating said rod to actuate said type-carriers and racks to their starting points.
22. In an adding machine, a series of stops, means for setting said stops to represent numbers, adding wheels, racks for actuating said adding wheels, pivoted elements supported by said racks, means for operating said racks to engage said pivoted elements with said stops, clearing mechanism for operating said racks and adding wheels in clearing operations, and means under control of a part of said clearing mechanism, for moving said pivoted elements to position in which they will not engage any of said stops during clearing operations.
23. In an adding machine, a series of stops, mechanism for setting said stops to correspond to the digits of numbers, adding wheels, racks for actuating said adding
- wheels, movable elements supported by said racks, means for operating said racks to engage said movable elements with said stops, means for operating said racks and said adding wheels in clearing operations, a device for moving said elements to position to prevent said elements from engaging said stops during clearing operations, and manipulative mechanism for actuating said device.
24. In an adding machine, a series of hammers arranged in numerical orders, pawls holding said hammers in retracted positions, bars for releasing said pawls, a permanent connection between each bar and the corresponding pawl, a coupler wholly supported by each bar and movable thereon into and out of position to cooperate with the adjacent bar, whereby the cooperative relation of said bars may be interrupted in any desired varying number of orders at the same time, manipulative devices arranged in numerical orders corresponding to said hammers for operating said couplers, and means for indicating the order of each of said devices.
25. In a machine of the character described, the combination of printing hammers, releasing devices therefor, a coupler wholly supported by one such device and movable thereon into and out of position to cooperate with the adjacent device, and a key wholly supported by each coupler, substantially as specified.
26. In a machine of the character described, the combination of printing hammers arranged in numerical orders, pawls engaging and holding said hammers in retracted positions, releasing devices for said pawls, a coupler wholly supported by one such releasing device and movable thereon into and out of position to cooperate with the adjacent device, and a settable device for moving said coupler on said releasing device and indicating visually the numerical order in which said coupler is located.
27. In an adding machine of the character described, the combination of printing hammers, members holding said hammers, devices for releasing said members from said hammers, couplers wholly supported by certain of said releasing devices and independently movable thereon into and out of position to cooperate with the adjacent devices, whereby the cooperative relation of said releasing devices may be simultaneously interrupted in varying numbers of different orders, and elements for moving said couplers into and out of position to cooperate with the adjacent devices and visually indicating the position of said couplers.
28. In a machine of the character described, the combination of printing hammers arranged in numerical orders, mem-

- bers holding said hammers, devices for releasing said members from said hammers, actuators arranged in numerical orders controlling the cooperation between several adjacent releasing devices, whereby the cooperative relation of said releasing devices may be interrupted in one or more orders as desired, and elements for holding said actuators in position to indicate visually whether 10 or not said releasing devices are in cooperative relation to each other.
29. In an adding machine, the combination of printing hammers arranged in numerical orders, releasing devices therefor, a coupler wholly supported by one such releasing device and movable thereon into and out of position to coöperate with the adjacent device, a latch carried by said coupler and engaging the releasing device for holding said coupler in each of its different adjustments, and a device carried by and movable with said coupler for visually indicating the position of said coupler.
30. In a machine of the character described, the combination with type-carriers, means for positioning said type-carriers for recording numbers, latches adapted to engage said type-carriers after they have been positioned, a rod normally holding said 25 latches disengaged from said type-carriers, a yielding device holding said rod to prevent said latches normally from engaging said type-carriers, and a link operating said rod to enable said latches to engage said type-carriers after said type carriers have been positioned.
31. In a machine of the character described, a support mounted stationary with respect to the framing of the machine, a series of elements in said support settable to represent numbers, actuating devices for setting said elements in position to represent numbers, manipulative mechanism operable to adjust said actuating devices in position 40 to actuate said elements, and an actuator timed to operate, after said actuating devices have been positioned as aforesaid, and controlled in said operation by said manipulative mechanism to move said actuating devices to set said elements.
32. In a machine of the character described, a support mounted stationary with respect to the framing of the machine, stops in said support settable to represent numbers, mechanism for setting said stops to represent numbers, numeral keys controlling said setting mechanism, and a motor controlled by said numerical keys for actuating said setting mechanism.
33. In a machine of the character described, the combination of stops arranged in numerical orders, numeral keys operable to set the stops in one of said orders to represent the digits of numbers, means under 50 control of the parts in said one order 65 for setting parts of corresponding value in an adjacent order incidentally to subsequent operation of said keys, and an actuator under control of the keys for operating said means.
34. In a machine of the character described, a number of movable parts arranged in numerical orders and adapted to be set to represent numbers, manual means for setting the parts in one order to represent the digits of numbers successively, a motor device, and means actuated by said motor device and under the control of the parts in said one order for setting parts of corresponding value in adjacent orders successively incidentally to subsequent operation of said manual means.
35. In a machine of the character described, a series of parts arranged in numerical orders adapted to be set to represent numbers, a movable carriage, levers mounted in said carriage, and numeral keys for actuating said levers in any position of said carriage to set certain of said parts to represent the digits of numbers.
36. In a machine of the character described, a series of parts arranged in numerical orders and adapted to be set to represent numbers, a carriage, means for moving said carriage to different positions, levers in said carriage operable to set certain of said parts to represent the digits of numbers in any position of said carriage, and numeral keys for actuating said levers.
37. In a machine of the character described, a series of parts arranged in numerical orders and adapted to be set to represent numbers, digit key mechanism operable to set the parts in one order successively to represent the digits of numbers, and means controlled by said digit key mechanism and by the parts in said order to set parts of corresponding value in adjacent orders incidentally to subsequent operation of said digit keys.
38. In an adding machine, a series of parts arranged in numerical orders and adapted to be set to represent the digits of numbers to be added, manual mechanism operable to set the parts in a selected order to represent successively all of the digits of each number to be added, and mechanism operating as an incident to successive operations of said manual mechanism and under control of each part in said selected order to set parts in an adjacent order of corresponding digital value to any parts set in the selected order in preceding operations.
39. In a machine of the character described, a series of parts arranged in numerical orders and adapted to be set to represent numbers, digit keys for setting the parts in one order successively to rep-

- resent digits of numbers, actuating devices controlled by the setting of said parts, and means for operating said actuating devices to set parts of corresponding value in adjacent orders incidentally to subsequent operation of any of said digit keys.
40. In a machine of the character described, the combination of series of parts arranged in numerical orders and adapted to be set to represent numbers, levers under control of the operator for selectively setting the parts in units order successively to represent the digits of numbers, and elements positioned by the setting of parts in units order for setting parts of corresponding value in adjacent orders incidentally to subsequent operation of any of said levers to set parts in units order.
41. In a machine of the character described, the combination of movable stops arranged in numerical orders and adapted to be set to represent numbers, a carriage movable to different order positions relative to said stops, means for positioning and holding said carriage in different selected order positions, levers pivoted in said carriage, and numeral keys supported independently of said carriage for actuating and causing said levers to set selected stops in one order.
42. In a machine of the character described, the combination of parts arranged in numerical orders and adapted to be set to represent numbers, keys for setting the parts in one order successively to represent the digits of numbers, a motor, and mechanism controlled by said motor to set parts of corresponding value to the parts set by said keys.
43. In a machine of the character described, the combination of parts arranged in numerical orders and adapted to be set to represent numbers, keys for setting the parts in one order successively to represent the digits of numbers, a motor, and mechanism controlled by said motor to set parts of corresponding value to the parts set by said keys, incidentally to subsequent operation of said keys.
44. In an adding machine, the combination of a support mounted stationary with respect to the framing of the machine, parts arranged in numerical orders in said support adapted to be set to represent numbers, keys operable to set the parts in one order successively to represent the digits of numbers, automatic mechanism for setting parts of corresponding value in adjacent orders incidentally to successive settings of parts in the first order and mechanism operated incidentally to the usual adding operations of the machine for restoring said parts to their idle positions.
45. In an adding machine, a stationary support, elements in said support adapted to be set to represent numbers, key mechanism for initially setting said elements to represent the digits of numbers, and means controlled by certain of said elements to set elements of corresponding digital value incidentally to subsequent operation of said keys to effect initial setting of others of said elements to represent the digits of numbers.
46. In an adding machine, differential mechanism comprising a series of stops arranged in numerical orders, manual mechanism for setting the stops in units order to represent successively all of the digits of each number to be added, means positioned by the setting of a stop in units order for setting a stop in an adjacent order of corresponding value to any stop set in units order in a preceding operation, and mechanism for operating said means.
47. In an adding machine, differential mechanism comprising a series of stops arranged in numerical orders, numeral keys separate from said stops operable to set said stops in units order successively to represent all of the digits of each number, pawls arranged to be operated by said stops in units order respectively incidentally to the setting of said stops to represent digits of numbers, and means for actuating said pawls respectively to set stops of corresponding value in adjacent orders as an incident to subsequent operations of said numeral keys to set stops in units order.
48. In an adding machine, a series of key levers, finger keys mounted on said levers, stops arranged in numerical orders, stop setting levers actuated by said key levers for setting the stops in certain of said orders, and motor actuated mechanism for setting stops of corresponding value to those set by said levers.
49. In an adding machine, the combination with numeral key levers, and a row of stops corresponding to a numerical order settable by said keys successively to represent the digits of numbers, of additional rows of stops corresponding to numerical orders, and a motor actuated mechanism controlled by said numeral key levers for setting stops in said additional orders of corresponding value to the stops set by the operation of said key levers.
50. In an adding machine, the combination with a series of stops, and mechanism for setting said stops to represent numbers, of type-carriers, mechanism for operating said type-carriers, means to engage said stops to limit movement of said type-carriers, latching means engaging said type-carriers after their movement has been stopped by said stops, and means for restoring said stops to idle position while said type-carriers are held by said latching means.
51. In an adding machine, digit stops ar-

- ranged in numerical orders, manually depressible numeral keys for setting the stops in units order successively to represent the digits of numbers, stop actuating elements positioned by the stops of each order for setting stops of corresponding digital value in adjacent orders, and means for actuating said stop actuating elements to set stops in adjacent orders incidentally to the manual depression of any one of said numeral keys after one or more of said stops has been set. 5
52. In an adding machine, a support, digit stops mounted in said support, manually depressible numeral keys operable to set certain of said stops to represent the digits of numbers, a movable support, elements in said movable support positioned incidentally to the setting of stops by said numeral keys, and connections controlled by 15
- 20 said numeral keys for actuating said movable support and said elements to set stops of corresponding digital value to the stops set by said numeral keys incidentally to the subsequent manual depression of any 25 one of said numeral keys.
53. In an adding machine, stops arranged in numerical orders and adapted to be set to represent numbers, keys operable to set the stops in one order to represent the digits 30 of numbers successively, and motor actuated mechanism operable to set stops of corresponding value to those set by said keys incidentally to subsequent operation of said keys to set stops in said first-named order. 35
54. In an adding machine, a rigid support, stops mounted in numerical orders in said support, keys operable to set stops in one order, a carriage, and means for moving said carriage to different adjusted positions 40 with respect to said stops and said support whereby stops in additional orders may be set by operation of said keys while said carriage remains stationary in said adjusted positions. 45
55. In an adding machine, the combination with a series of stops arranged in numerical orders, of a carriage, levers in said carriage operable to set said stops to represent the digits of numbers, means for moving said carriage and said levers to set stops of different orders, and mechanism for selectively operating said levers to set stops in any position of said carriage. 50
56. In an adding machine, the combination with a series of stops arranged in numerical orders, of a carriage, a series of levers in said carriage for setting said stops to represent numbers, means for positioning said carriage and said levers to set stops 55 in different orders, and means for operating selectively said levers in any position of said carriage. 60
57. In an adding machine, a series of stops arranged in numerical orders, a carriage, a series of ten levers in said carriage 65
- corresponding to the numerical characters or digits, means for moving said carriage and levers to different selected positions, and means for selectively operating said levers to set certain of said stops in any position of said carriage. 70
58. The combination of a series of printing hammers, pawls holding said hammers, releasing bars pivoted to said pawls, a coupler wholly supported by one such bar and movable thereon into and out of position to coöperate with the adjacent bar, and a key supported by said coupler. 75
59. In a machine of the character described, the combination of printing hammers mounted in numerical orders, pawls holding said hammers, releasing bars pivotally connected to said pawls respectively, couplers supported by certain of said bars and movable thereon into and out of position to coöperate with the adjacent bars, actuators arranged in numerical orders for actuating said coupler and settable in different positions conforming to the positions of the couplers, and devices for visually designating the order in which each of said actuators and its coupler are mounted. 80
60. In an adding machine, the combination with rows of settable stops arranged in numerical orders, devices for setting the stops in units order successively one at a time, appliances for setting stops in adjacent orders of corresponding value to the stops first set in units order as an incident to subsequent setting of stops in units order, and a motor for operating said appliances, of a series of ten numeral keys corresponding respectively to the ten digits, and means under control of said numeral keys controlling said motor. 100
- 105
61. In an adding machine, the combination with a stationary frame, a series of rows of settable stops arranged in numerical orders in said frame, devices for setting the stops in units order successively one at a time, appliances for setting stops in adjacent orders of corresponding value to the stops first set in units order as an incident to subsequent setting of stops in units order, and a motor for actuating said appliances, of a series of ten numeral keys corresponding respectively to the ten digits determining which of said stops will be set in units order and controlling said motor. 110
- 115
62. In an adding machine, a stationary frame, rows of settable stops arranged in numerical orders in said frame, a movable frame, appliances in said movable frame for setting stops in adjacent orders of corresponding value to the stops first set in units order as an incident to subsequent setting of stops in units order, means for controlling said appliances, and a motor for actuating said appliances to set said stops as aforesaid. 120
- 125
- 130

63. In an adding machine, a stationary frame, series of settable stops in said frame, a movable frame, elements in said movable frame operable to set said stops, levers controlling the positioning of said elements, key levers for actuating said first-named levers, and a motor for actuating said elements to set said stops.
64. In an adding machine, a series of settable stops, a series of ten numeral key levers, a carriage movable to different selected positions, means for holding said carriage stationary in its different selected positions, and a series of ten levers mounted in said carriage under control of said numeral keys for selectively setting said stops while said carriage is stationary in any of its selected positions.
65. In an adding machine, series of settable stops, a series of ten numeral key levers, a support adjustable in different selected positions, and a series of pivoted levers in said support under control of said key levers for selectively setting said stops in any adjusted position of said support.
66. In an adding machine, the combination with a series of denominational rows of settable digit stops, a carriage movable to different selected adjustments, a number of levers pivoted in said carriage, a series of ten numeral key levers controlling said pivoted levers to set selected ones of said stops while said carriage is stationary in any of its adjusted positions.
67. In an adding machine, a series of denominational rows of settable stops, a movable carriage, levers pivoted in said carriage, means for moving said carriage to different selected adjustments so that said levers may control the setting of stops in different denominational rows and numeral key levers operable to actuate said first-named levers selectively to set selected stops while said carriage is stationary in any adjusted position.
68. In an adding machine, a series of denominational rows of settable stops, pivoted pawls for setting said stops, means for selecting which of said pawls shall be operated, and motor mechanism for actuating said pawls to set the selected stops.
69. In an adding machine, a support mounted stationary with respect to the framing of the machine, a series of denominational rows of settable stops in said support, manipulative mechanism for successively setting the stops in units row to represent the digits of numbers, pivoted elements moved by the setting of the stops in said units row, and mechanism for moving said pivoted elements to set stops in an adjacent row as an incident to the successive operations of said manipulative mechanism to set a stop in units row.
70. In an adding machine, a series of denominational rows of settable stops, a motor, numeral keys controlling said motor, supports, pivoted pawls upon said supports, and means whereby said lever will operate said supports and said pawls to set said stops.
71. In an adding machine, a series of denominational rows of settable stops, key mechanism for setting stops in one row, and motor actuated mechanism for setting the stops of corresponding value in adjacent rows incidentally to subsequent operation of said keys.
72. In an adding machine, a series of denominational rows of settable stops, latch devices for holding said stops after they have been set, levers operable to set the stops in one row successively, and motor actuated mechanism for setting stops of corresponding value to stops set in the preceding operation incidentally to subsequent operation of said levers.
73. In an adding machine, the combination with a series of movable type-carriers, means for positioning said type-carriers to record, a series of latches, a rod normally holding said latches disengaged from said type-carriers, a latch device controlling said rod, means for moving said rod to enable said latches to engage said type-carriers after said type-carriers have been positioned for recording, and springs actuating said latches into engagement with said type-carriers.
74. In an adding machine, a series of type-carriers, means for moving said type-carriers to recording position, latches, a rod normally holding said latches disengaged from said type-carriers, means for moving said rod to enable said latches to engage said type-carriers after said type-carriers have stopped in recording position, springs for engaging said latches with said type-carriers, means for restoring said type-carriers to idle position, and means for disengaging said latches from said type-carriers.
75. In an adding machine, a series of type-carriers, means for moving said type-carriers to recording position, latches, a rod normally holding said latches disengaged from said type-carriers, means for moving said rod after said type-carriers have stopped in recording position, means for engaging said latches with said type-carriers, and means for disengaging said latches from said type-carriers after the record has been made.
76. In an adding machine, a series of type-carriers, means for moving said type-carriers to recording position, latches, a rod normally holding said latches disengaged from said type-carriers, a latch device controlling said rod, means for moving said rod after said type-carriers have been stopped in recording position, springs actuating said

latches into engagement with said type carriers, and means for actuating said rod to disengage said latches from said type-carriers after the record has been made.

- 5 77. In an adding machine, the combination of a number of movable parts arranged in numerical orders and adapted to be set to represent numbers, means controlled by the setting of a part in units order for setting a part of corresponding value in adjacent orders incidentally to subsequent setting of any other part in units order, latches for holding said parts in the positions in which they are set, mechanism under control of said parts for adding the numbers represented by said parts, and means operated incidentally to the adding operation for releasing said latches.
- 10 78. In an adding machine, the combination of a series of type-carriers movable to and from recording positions, differential mechanism for stopping said type-carriers in their recording positions, a support extending transversely of said type-carriers, 25 pawls mounted on said support above said type-carriers, a rod holding said pawls out of engagement with said type-carriers during movement of said type-carriers to their recording positions, means for moving said rod away from said pawls to enable said pawls to be moved into engagement with said type-carriers after said type-carriers have been stopped in their recording positions by said differential mechanism,
- 30 35 springs coöoperating with said rod to actuate said pawls into engagement with said type-carriers, means for moving said rod to disengage said pawls from said type-carriers

as an incident to the return of said type-carriers to their idle positions, and means 40 for holding said rod in position to hold said pawls out of engagement with said type-carriers.

79. In an adding machine, the combination of a series of type-carriers movable to and from recording positions, differential mechanism for stopping said type-carriers in their recording positions, a series of pawls supported above said type-carriers, a rock shaft, an arm supported by said rock shaft, a lever supported by said rock shaft, a rod supported by said arm and said lever for holding said pawls out of engagement with said type-carriers, a device for holding said rod in position to hold said pawls out of engagement with said type-carriers during movement of said type-carriers to recording positions, an actuating device for moving said rod to enable said pawls to engage with said type-carriers after said type-carriers have been stopped in their recording positions by said differential mechanism, 55 springs for actuating said pawls into engagement with said type-carriers, and means for causing said actuating device to move said rod to disengage said pawls from said type-carriers as an incident to the movement of said type-carriers from their recording positions.

In witness whereof, I have signed this 70 specification in the presence of two subscribing witnesses.

HARRY LANDSIEDEL.
